UNITED STATES PATENT OFFICE

DONALD S. BARROWS, OF ROCHESTER, NEW YORK, ASSIGNOR TO THE GOULD COUPLER COMPANY, OF DEPEW, NEW YORK, A CORPORATION OF MARYLAND

SIDE FRAME

Application filed August 31, 1928. Serial No. 132,737.

This invention relates to side frames and, more particularly, to such frames for railway car trucks which are integrally formed by casting.

5 The principal object of my invention, generally considered, is the provision of a cast side frame for railway car trucks in which the tension member thereof is specially reinforced at the junction between its central or 10 intermediate substantially horizontal portion and the diagonal end portions thereof.

An object of my invention is the provision of a cast side frame for railway car trucks in which the tension member is generally U 15 shape in cross section and the lower web thereof is bulged downwardly at the junction between the horizontal intermediate portion and the diagonal end portions for increasing the strength of the frame at these 20 points.

Another object of my invention is the provision of a truck side frame integrally formed with a tension member generally U shape in cross section and bolster guide columns extending upwardly therefrom, said tension 25 member being normally horizontal between said bolster guide columns with end portions extending diagonally upward and outward therefrom, the web of said tension 30 member, beneath the guide columns, being first curved downwardly from the end portions and then curved upwardly to join with the horizontal intermediate portion immediately beneath each bolster guide column 35 for increasing the strength of the frame at these points.

Other objects and advantages of the invention relating to the particular arrangement and combination of the various parts 40 will become apparent as the description proceeds.

Referring to the drawings illustrating my invention, the scope whereof is pointed out in the appended claims:

45 Figure 1 is a partial side elevation, shown partly in section, of a side frame embodying my invention.

Figure 2 is a transverse sectional view on the line 2—2 of Figure 1.

50 Figure 3 is a horizontal sectional view on

the line 3—3 of Figure 1 looking in the direction of the arrows.

Referring to the drawings in detail, like parts being designated by like reference characters, there is illustrated the lower central portion of a side frame 1 especially adapted for railway car trucks, the remainder of said frame, being of old or well known construction and not involving features of my present invention, not being illustrated. 55

In the embodiment shown, the frame comprises a tension member 2 with bolster guide columns 3 extending upwardly therefrom. The lower ends of the columns merge into the tension member with the junctions preferably filleted or curved as illustrated. As will be understood, the side frame is symmetrical and said bolster guide columns are adapted to space the intermediate portion of the tension member 2 from a compression member 60 (not shown) and the ends of said compression and tension members join adjacent journal boxes (not shown) or portions of the frame adapted for connection with journal boxes. 65

In the present embodiment of my invention, the tension member 2, between the bolster guide columns 3 which, with the tension and compression members, define a bolster or window opening 4, is normally horizontal 70 and of uniform or substantially constant depth, and those portions outside of the bolster guide columns 3 extend diagonally upward and outward in accordance with usual construction. Instead, however, of the lower 75 web 5 of the tension member extending straight down from the end portions to join with the intermediate horizontal portion of said web and curving only in one direction, that is, upwardly at said junction, said web 80 5, in accordance with my invention, is first formed concave downwardly as indicated at 6 and then formed concave upwardly as indicated at 7. The centers or axes of curvature 85 of the portions 7 concave upwardly preferably correspond substantially with the centers or axes of the corresponding fillets between the inner or adjacent faces of the columns and the upper web 8 of the tension member. 90

The axes of curvature are there- 95 100

fore disposed above the tension member, the radii being longer than the depth thereof. Said web 5, in passing from the diagonal end portions of the tension member to the horizontal portion thereof beneath each bolster guide column, is thus first curved in one direction, that is, downwardly and then curved in the other direction, that is, upwardly, forming a bulge beneath each bolster guide column at the junction between the diagonal portions of the tension member and the horizontal portion thereof, whereby said tension member is materially increased in strength at said junctions and where it joins with the bolster guide columns. Inasmuch as these junctions are critical portions of the side frame, such increases in strength improve the general strength of the frame as a whole without involving any material increase in the weight thereof.

Although the tension member 2 is generally U shape in cross section, yet it is preferably formed with an upper substantially flat web 8 between the bolster guide columns 3 forming a spring plank seat portion which may be provided as usual with A. R. A. squaring lugs 9. Said spring plank seat portion 8, being wider than the normal width of the tension member, is preferably braced beyond the side webs or flanges 10 of said tension member by triangular gusset or bracing portions 11. Beyond the spring plank seat portion, beneath the bolster guide columns, the external portions or portions extending beyond the webs 10 of the tension member are tapered off to merge with said tension member beyond the bolster guide columns as indicated at 12. It will be noted that although these continuations are extended diagonally upward, yet the angularity thereof is not quite as great as that of the end portions of the tension member.

The intermediate portion of the spring plank seat 8 or that portion between the webs or flanges 10 of the tension member is bifurcated beneath the bolster guide columns and tapered off to merge with the side webs or flanges 10 of the tension member as indicated particularly at 13. It will be noted that the angularity or inclination of these extensions 13 is greater than that of the extensions 12 although not as great as the general inclination of the end portions of the tension member 2.

Although only a portion of the side frame has been illustrated so as to more clearly point out the invention, it will be understood that the remainder of the frame which is not illustrated may conform to standard or desirable practice in connection with the normal manufacture of such frames.

From the foregoing disclosure, it will be apparent that I have invented a side frame in which the strength thereof and particularly the strength of the tension member at the

junctions with the bolster guide columns is much increased without involving any material increase in weight or size of said frame and, as these junctions are critical portions of the frame, a general improvement in the construction thereof has been effected.

Having now described my invention, I claim:

1. A side frame comprising a tension member formed with a lower web and upstanding flanges on the sides of said web, said tension member being formed with a central or intermediate horizontal portion formed with an upper web extended beyond the sides of the member to provide a spring plank seat portion, and upwardly and outwardly extending end portions, the upper web of said member beyond the sides thereof being continued upwardly and outwardly along the end portions and tapered to merge with the sides of the frame, above but closer to the webs of the end portions of the tension member than the top edges of the flanges thereof, the lower web of said member, where each end portion joins the central or intermediate portion, being first concave downwardly and then concave upwardly for increasing the strength of the member at said junctions.

2. A side frame comprising a tension member generally U shape in cross section, the intermediate portion thereof being substantially horizontal and formed with an upper web extended laterally beyond the sides of the member to provide adequate spring plank seat area, and the end portions extending diagonally upward therefrom, the upper web of said member between the sides thereof being bifurcated adjacent the ends of the intermediate portion and tapered upwardly and outwardly to merge into the side walls of the frame, the lower web of said member, at each junction between an end portion and the intermediate portion, being bulged downward to strengthen said member at said junctions.

3. A side frame comprising a tension member and bolster guide columns extending upward therefrom, said tension member being generally U shape in cross section, the portion thereof, between the bolster guide columns, being normally horizontal and formed with an upper web extended beyond the sides of the member to provide a spring plank seat, the portions, on opposite sides of said columns, extending diagonally upward therefrom, the upper web of said member beyond the sides thereof being continued beneath the guide columns upwardly and outwardly along the end portions and tapered to merge into the sides of the frame, the plane of said web being disposed between the planes of the web and upper edges of the flanges of the diagonal end portions of the tension member, the lower web of said tension member, immediately below each bolster guide column, curving down-

ward at the end portions of said member and then curving upward to joint with the horizontal portion of said member for increasing the strength at the junction with the 5 bolster columns.

4. A side frame comprising a tension member formed with a lower web and upstanding flanges on the sides of said web, bolster guide columns extending upwardly therefrom and integral therewith, that portion of the tension member, between the bolster guide columns, being normally horizontal and formed with an upper web extended beneath the guide columns, and those portions, outside 10 of said columns, extending upwardly and outwardly therefrom, the upper web of said member between the sides thereof being bifurcated beneath the guide columns with the bifurcations tapered upwardly and outwardly 15 to merge into the side walls of the frame, the lower web of said tension member, immediately below each guide column, being concave downwardly adjacent the end portions of the member and then concave upwardly adjacent the horizontal portion of the member for increasing the strength at the 20 junctions with the bolster guide columns.

5. A side frame comprising a tension member formed with a lower web and upstanding flanges at the sides of said web, said tension member being formed with an intermediate substantially horizontal portion with an upper web extended beyond the sides of the member to provide a spring plank seat portion of the desired width, and upwardly and outwardly extending end portions, the upper web of said member beyond the sides thereof being continued upwardly and outwardly along the end portions and tapered to merge 30 with the sides of the frame between the planes of the webs of said end portions and the upper edges of the flanges thereof, the lower web of said member, where each end portion joins the intermediate portion, being first concave and then convex downwardly, for maintaining the depth of the member where the end portions join the intermediate portion, those portions of the upper web of the intermediate portion beyond the sides 35 thereof being reinforced by triangular gussets extending from the sides of the tension member.

6. A side frame comprising a tension member and bolster guide columns extending upwardly therefrom, said tension member being generally U shape in cross section, the portion thereof between the guide columns being normally horizontal and formed with an upper web extended beyond the sides of 40 the member and reinforced by outwardly extending triangular gussets from the sides of said member to said extended portions of the web to provide a spring plank seat, the portions of said tension member on opposite 45 sides of the columns extending diagonally.

upward therefrom, the upper web of said member beyond the sides thereof being continued diagonally upward and outward along the lower portions of the guide columns and the end portions of the tension member and 70 tapered to merge into the sides of the frame, the plane of said web being disposed between the lower web of the end portions and the upper edges of the flanges thereof, the lower web of said tension member adjacent the 75 junctions between the guide columns and the ends and intermediate portion of the tension member curving first upward as it is continued outward from the intermediate portion and then downward to align generally 80 with the webs of the diagonal end portions.

7. A side frame comprising a tension member generally U-shaped in cross section, the intermediate portion thereof being substantially horizontal and having an upper web 85 extended laterally beyond the sides thereof to provide adequate spring plank seat area, the end portions of said web extending diagonally upward therefrom between the sides of the tension member and 90 bifurcated adjacent the ends of the intermediate portion, said bifurcated portions being tapered upwardly and outwardly to merge into the side walls of said member, the lower web of said member being curved first one 95 way and then the other to unite the end and intermediate portions thereof and strengthen the junction therebetween.

8. A side frame comprising a tension member having a lower web and upstanding flanges on the sides thereof, bolster guide columns extending upwardly therefrom, that portion of the tension member between the guide columns being normally horizontal and having an upper web extended beneath 100 said guide columns, those portions of the member outwardly of said columns extending diagonally upward therefrom, the upper web of said member between the flanges thereof being bifurcated beneath the guide columns, 105 with the parts thereof tapered upwardly and outwardly to merge into the flanges of said member, the lower web of said tension member being curved directly beneath the guide columns to unite the horizontal and diagonal 110 portions thereof.

In testimony whereof I affix my signature.

DONALD S. BARROWS.
